UNITED STATES PATENT OFFICE.

ANNA K. MAY, OF PHILADELPHIA, PENNSYLVANIA.

DESIGN FOR CARPET.

SPECIFICATION forming part of Design No. 26,050, dated September 15, 1896.

Application filed July 30, 1896. Serial No. 601,105. Term of patent 3½ years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part hereof.

My design is of the style of the sixteenth century and its leading feature is a panel within or upon which appears a chintz-pattern and chains of conventional flowers. The color-

ing and kind of carpet employed are not material to my design and consequently may be varied.

In the drawing, *a* is the body, *b* the border, and *a b* the complete carpet.

c is a panel within which appears a chintz-pattern *d*, composed of flower and leaf forms. *e* are chains of conventional flowers.

What I claim as my invention, and desire to secure by Letters Patent, is—

1. In a design for a carpet, the body *a*, substantially as shown.

2. In a design for a carpet, the border *b*, substantially as shown.

3. The design for a carpet consisting of the body *a*, and border *b*, substantially as shown. 30

In testimony whereof I have hereunto signed my name in the presence of two witnesses.

ANNA K. MAY.
